Andre Pallapies; Brandon G. Braun(57) **CLAIM**

We claim the ornamental design for an induction cooktop, as shown and described.

DESCRIPTION

FIG. 1 is a perspective view of an induction cooktop, showing our new design;

FIG. 2 is a top plan view thereof;

FIG. 3 is a bottom plan view thereof;

FIG. 4 is a left side elevational view thereof; and,

FIG. 5 is a front elevational view thereof.

Broken lines are for illustrating unclaimed portions of the induction cooktop; the broken lines form no part of the claimed design. All text and numbers shown in FIGS. 1-2 are disclaimed and depicted with broken lines. A right side elevation view is identical to the left side elevational view as shown in FIG. 4, and a rear elevational view is identical to the front elevational view as shown in FIG. 5.
